COSMETIC APPLICATOR

Joseph Pepin, 8846 Stewart Ave., Los Angeles, Calif.
Filed Aug. 17, 1959, Ser. No. 834,048
1 Claim. (Cl. 132—79)

The present invention relates broadly to a cosmetic applicator and more specifically to a type of applicator using a ball for the application of the cosmetic to the lips.

The inventor is aware that ball points are of general usage in many devices such as pens, deodorant applicators, eye-brow pencils, to name a few. However, ball point pens and deodorant applicators have problems different from that faced by a ball point applicator for lip cosmetic. To illustrate, it is essential in ball point applicators that the lip cosmetic be suitably held within a barrel in such a manner as not to leak past the ball during rapid temperature changes, or regardless of the position assumed by the applicator, and still be immediately operable when it is desired to apply the lip cosmetic to the lips. Furthermore, a ball point applicator must not drag over the lips so as to cause abrasion or soreness thereof. Most people using lip cosmetics desire initially to make a fine line so as to outline the lips, followed by a rapid filling in of the lips with the cosmetic.

The present invention accomplishes the various desired functions above enumerated in that it allows instant application of the lip cosmetic without undue pressure of the ball against the lips and wherein the ball immediately opens or closes to a seat to seal against leak of the cosmetic.

Other objects include a cosmetic applicator which functions in an efficient manner, is superior to applicators now known to the inventor, inexpensive in cost of manufacture, and attractive in appearance.

With the above mentioned and other objects in view, as will appear from the specification, the invention consists in the novel and useful provision, formation, construction, association and relative arrangement of parts, members and features, all as disclosed in one embodiment in the accompanying drawing, described generally and more particularly pointed out in the claim.

In the drawing:

FIGURE 1 is a fragmentary, partially sectional detached view of the invention;

FIGURE 2 is a sectional view, on an enlarged scale, taken on the line 2—2 of FIGURE 1;

FIGURE 3 is a fragmentary, longitudinal sectional view of the barrel shown in FIGURE 2, certain parts being in changed position;

FIGURE 4 is a sectional view on an enlarged scale of one form of piston used in the practice of the invention;

FIGURE 5 is a sectional view on the line 5—5 of FIGURE 1, on an enlarged scale; and,

FIGURE 6 is a longitudinal sectional view of another form of piston which may be used in the practice of the invention.

Referring to the drawing, I have shown in FIGURES 1 and 2 an elongated barrel 1 within which is a piston 2 of some form, such as is illustrated in FIGURES 4 and 6, adapted to be moved axially of the barrel by a helical spring 3 so as to exert a pressure against lip cosmetic 4 to move the same forwardly toward finger piece 5 which carries tip 6, the tip rotatably supporting a ball 7. The spring 3 is held within the barrel between the piston 2 and a retainer plug 8 formed with a central bore. The barrel 1 is positioned within a casing 9 which is provided with a cap 10.

The barrel 1 is substantially uniform in diameter, and may have a predetermined size and length, so as to confine a preselected amount of lip cosmetic, which is usually a colored viscous homogeneous flowing cream. The barrel

2

may be formed from various materials although nylon has been found satisfactory in that it does not contaminate the lip cosmetic 4. Lip cosmetics must be selected from ingredients that are non-toxic and preferably non-acid, but if such cosmetic does have an acid reaction or a pH under 7, the barrel must be formed from a material which is not attacked by the cosmetic. It is essential that the bore inside the barrel is smooth and without high or low spots which might impair movement of the piston 2. 10 The piston 2 is preferably formed from a polyethylene due to the flexibility of this material. Thus, in FIGURE 6, by way of example, the piston has an annular feather edge 11, the piston being of a type wherein the main body has a conical cup 12, a base stud or projection 13 and a tapered outer side wall 14 which side wall merges with the conical wall of the cup 12, thus providing a variable thickness side wall which, as stated, terminates in the feather edge 11. Substantially the same structure is provided in FIGURE 4, the difference being that the cup is 20 not as deep as the cup shown in FIGURE 6. However, a feather edge is provided at 15. The feather edge diameter of the piston is slightly greater than the bore diameter of the barrel 1 to the end that the feather edge is compressed so as to have frictional engagement with the wall bounding the bore in the barrel. In actual practice I have found it expedient to have the outside diameter of the feather edge of the piston .001" greater than the bore diameter of the barrel. The feather edge has wiping engagement with the barrel without appreciable drag during movement thereof.

Within the barrel and between the retainer plug 8 and the stud 13 of the piston, is the helical spring 3, which usually is provided at its ends with inactive coils, and which helical spring is of the compression type with sufficient coils provided to move the piston from the position of FIGURE 2 to that of FIGURE 3, to progressively discharge the lip cosmetic as it is applied by the ball applicator 7 to a surface such as the lips. The number of coils required for the spring 3 is a matter of calculation and reference is made to such texts as "Mechanical Springs" by Wahl, published by Penton. Thus the number of coils for the spring, the diameter and character of the spring wire which is usually a piano wire, may be calculated so as to move a given mass such as the cosmetic 4 of known specific gravity forwardly under constantly acting pressure when the ball applicator 7 is unseated. By way of example, I might say that I have continuously moved lip cosmetic, having a specific gravity between 1.1 and 1.2, forwardly by the piston, using a coil spring formed from No. 6 piano wire. The spring pressure was 4½ ounces and initially there was 1½ grams of lip cosmetic within the barrel. The No. 6 piano wire spring had 29 active coils and 5 inactive coils at each end, the main diameter of the coils being .265 inch with a solid height of .265 inch. 55 The overall length of the helical spring including the active coils and the inactive coils, was $3 \pm \frac{1}{16}$ inch.

The finger piece 5 has a tapered outer surface and a conical inner bore 16. This bore connects with a bore of uniform diameter 17. It will be noted that the base end of 60 the finger piece 5 has a reduced diameter annular sleeve 18 which forms a step at 19. In the present instance the casing which surrounds the barrel has an external reduced diameter portion 20 which engages and surrounds the sleeve 18 and is of a thickness so as to form a flush outer surface engagement with the finger piece 5. The barrel 1 is forced within the tapered bore 16 of the finger piece. It has been found that this is sufficient to hold the barrel in working engagement with the finger piece without leakage of the lip cosmetic between the barrel and the sleeve 18 of the finger piece. The tip 6 has a uniform diameter portion 21 which has close fit engagement with the uniform diameter portion 17 of the finger piece. The external sur-

face of the tip is of conical form at 22 so as to be flush with the conical surface of finger piece 5 and the bore of the said tip is of uniform diameter, as shown. The ball 7 fits within a socket in the tip 6, the tip being broached at 23 so as to overlie a small circle of the ball 7 to hold the ball within the socket. The ball has at least .001 of an inch play within the socket with the result that when the ball is in its forward position, as shown in FIGURE 2, it seats and thus prevents flow of lip cosmetic 4 under pressure past said ball. The slight play allowed the ball within the socket is sufficient, when the ball is pressed inwardly to unseat the same, to allow the ball to rotate readily and during rotation carry on the periphery thereof, lip cosmetic for application to the lips. Preferably the ball 7 is formed from glass, or Pyrex the periphery of which is frosted. Metal balls are not satisfactory in the practice of my invention as the ball must be truly spherical, not oxidizable nor effected by the ingredients of the lip cosmetic. The interstices provided by the frosted surface of the ball permits the lip cosmetic to adhere to the ball for ready application to the lips. Thus in the showing of my invention, I have found that a ball having a diameter of .1562 inch is satisfactory when the other dimensions and pressures previously given are adhered to. One-half ounce pressure inwardly against the ball is sufficient to unseat it.

The operation, uses and advantages of the invention are as follows.

In the beginning I enumerated several features of the present applicator which I deem to be novel in this art. Briefly, the applicator does not leak when not in use, the lip cosmetic is easily applied to the lips with slight pressure on the ball applicator, and there is a constant feeding of the lip cosmetic to the ball applicator and in such a manner that substantially all of the lip cosmetic in the barrel is used thereby preventing waste thereof. Further, the materials used in the construction of this applicator are such as to be trouble free and without contaminating the lip cosmetic. As I have previously pointed out, the number of coils for the helical spring 3 is a matter of calculation, based on the fact that the lip cosmetic preferably has a specific gravity of from 1.1 to 1.2. Usually in applicators of the type described, approximately one and one-half grams of lip cosmetic is used. The cosmetic having the specific gravity named, must be a viscous homogeneous flowing type cream. The conical wall 16 of the finger piece 5 acts to direct the lip cosmetic forwardly toward the ball applicator 7 without creating pockets which might hinder the even flow of the lip cosmetic to the ball. The specific gravity of the lip cosmetic being known, the spring pressure against the piston may be calculated so that the ball 7 may be unseated within the tip socket under light pressure of say, one-half ounce. I have found that the initial starting pressure which must be exerted by the spring against the piston to move the lip cosmetic, is approximately 45 grams and that the spring requires approximately 130 grams to fully compress the same. It is important that the ball applicator readily rotate within the socket of the tip and I have determined that a clearance in the socket of .001 inch is sufficient.

The central hole in the retainer plug 3 allows the barrel to the rear of the piston to be under atmospheric pressure, and the casing may be provided with a small hole if found necessary.

5 The construction is such that only the feather edge of the piston engages the barrel, thus lessening drag therebetween. The lip cosmetic is received in the bellmouth portion of the piston 2, which causes outward expansion of the piston wall and assures against leakage between the feather edge and the barrel. Thus cosmetic is not received back of the piston, which might impair spring action.

I claim:

15 A lip cosmetic applicator including: a finger piece having a central internal conical bore merging at each end into a cylindrical bore, one cylindrical bore being larger than the other, a tip secured to said finger piece in the smaller cylindrical bore and communicating with the conical bore, the outer end of said tip being formed with a socket, a ball within said socket, a barrel having a cylindrical bore, one end of the barrel having a pressed fit engagement extending within the larger cylindrical bore of the finger piece, the opposite end of said barrel provided with a retainer plug having a hole therethrough, a 20 piston within said barrel, said piston having a main portion smaller in diameter than the bore of the barrel and a head provided with a bell mouth with a central spheroidal bottom merging into a feather edge having a wiping engagement with the bore of the barrel, a coil spring of 25 a diameter about equal to its solid length when compressed between the piston and the retainer plug, the space between the piston head and the ball being filled with a viscous homogeneous flowing cosmetic, the said spring being so formed as at all times to exert sufficient 30 compressive pressure against the piston to move the cosmetic toward the ball and the ball unseating within the socket of the tip under a pressure of less than one-half ounce, whereby a thin margin line of cosmetic may be discharged as a desired outline and later a greater supply 35 of cosmetic may be discharged upon application of a greater pressure on the free surface of the ball, making it easier to fill in the space on the lips outlined by the fine line margin.
